UNITED STATES PATENT OFFICE.

FRANCIS D. HAYWARD, OF MALDEN, AND IRA E. SANBORN, OF BOSTON,
MASSACHUSETTS, ASSIGNEES OF JOHN C. BICKFORD.

IMPROVED PROCESS FOR ROLLING INDIA-RUBBER CLOTH.

Specification forming part of Letters Patent No. 7,189, dated March 19, 1850; extended seven years; Reissue No. 2,207, dated March 20, 1865.

To all whom it may concern:

Whereas Letters Patent No. 7,189 were granted to FRANCIS D. HAYWARD and JOHN C. BICKFORD, on the 19th day of March, of the year 1850, for a new and useful Process of Rolling India-Rubber Cloth, or, in other words, for coating cloth or other material with caoutchouc; and whereas the term for which such Letters Patent were originally granted has been extended by the Commissioner of Patents for a further period of seven years; and whereas we, the undersigned, have become, by assignment or otherwise, the sole proprietors of the said patent and the exclusive property covered thereby: Now, therefore, for the purposes of a reissue of the said patent, we do hereby declare the following to be a full and correct description of the invention of the said patentees.

The said invention or process consists in taking a piece of cloth and applying to it india-rubber in an adhesive state, so as to give to the cloth what, for convenience, we will call a "friction coat" of rubber.

To make the invention clearly understood, we will describe the ordinary process of coating cloths with rubber, in the performance of which the india-rubber is placed between a series of two or more hollow iron rolls heated internally by steam, and made to revolve by suitable machinery. The heat and the pressure soften and grind the rubber and various substances mixed with it into an adhesive plastic mass, which can be molded into desired shapes or spread upon cloth. The ordinary method of spreading rubber upon cloth has been to pass the cloth and the adhesive rubber between two or more revolving rolls, by the action of which the rubber has been spread out into an even sheet, covering the outside of the cloth. This sheet of rubber can, when cool, be stripped from the cloth and used for various purposes in manufacturing; or the cloth with its outside covering of rubber such as described can be used for carriage-covers or sundry other devices; but it has been found that for other purposes in rubber manufactures—such as machine-beltting, conducting-hose, linings of shoes, &c.—it was necessary that the rubber should be forced into

the body of the cloth and into the meshes or spaces left by the threads of the cloth, so that a cloth could be prepared with rubber forced into it and incorporated with its threads or fibers, so that the prepared cloth would be partially adhesive, and other coats of rubber could be added to it and made to adhere to it. The old process of accomplishing this latter was to dissolve india-rubber in spirits of turpentine or camphene until it was so soft that it could be spread upon cloth by means of rollers. This rubber dissolved in camphene was so much softer than the rubber made plastic by grinding between heated iron rollers that it was by simple pressure forced into the meshes of the cloth, and for some purposes accomplished the desired object. This method of manufacture was open to great objection on account of the expense of the camphene used in dissolving the rubber, the disagreeable odor imparted to the goods by it, the danger of fire or explosion, the necessity of great space in the factory for drying the goods before they could be used, and the injury to the goods caused by the qualities of the camphene. To obviate these difficulties many experiments were instituted by the said HAYWARD and BICKFORD, in order to dispense with the use of camphene and yet be able to produce cloth with what we call a "friction coat" of gum forced into and incorporated with the cloth. In order to accomplish this result in accordance with the invention of the said parties a series of hollow iron rolls heated internally by steam are to be employed and made to revolve by machinery. These rolls do not require very particular description, as they are familiar to rubber manufacturers. A series of two or more rolls can be used, although we prefer three as the best number, and one of the rolls (the middle one, for instance) must be made to move faster than the others, or faster than one of the others, in order to drive the rubber into the cloth.

The accompanying drawing exhibits a set of three of such rolls, *a b c*, with the cloth *C* and rubber *R* applied to them, the directions of rotary motion of such rollers as well as the direction of the movement of the cloth being indicated by arrows. *D* is the roller

from which the cloth proceeds. E is another roller, on which the cloth is wound after having been coated with the rubber. A quantity of the india-rubber previously prepared by being ground is placed between two of the rolls, which revolve until in a short time the mass of rubber is still further heated and softened and spread in a thick sheet or coat around the fast roll. The thickness of this coat may be such as may be desirable, according to the nature, quantity, and quality of cloth. The cloth, rolled on a suitable "reel," "roll," or "shell," is next to be brought to the machine, and is to have one end placed upon one of the slow rolls in order that it may be fed between it and the faster roll. The faster roll being the middle one of the set, as it revolves drives a portion of its rubber onto or through the meshes of the cloth and incorporates it with the threads of the cloth. In this process a portion of the sheet of rubber which covers the faster roll is collected into a mass (called by rubber-workmen the "bank") between the cloth and the faster roll, and this bank is rolled over and over by means of the action of the rollers, and assists in the operation of forcing the friction coat into the cloth. This is what we call, for convenience, the "friction coat," and the cloth so called can be immediately used in manufacturing. It is often necessary that the cloth should have a similar friction coat upon its other side, and this object is accomplished by reversing the cloth and again passing it in a similar way through the machine.

We do not wish to claim as the invention of the said HAYWARD and BICKFORD any particular difference in the speeds of the rolls used in carrying out the process. In practical manufacturing the speeds differ according to

the nature of the rubber and the ingredients combined with it, and according to the nature of the work, whether coarse or fine, heavy or light. A very good proportion in case of the ordinary thin cloths used for shoe-linings is that the slower rolls should make six revolutions while the faster roll makes nine revolutions; but in coating the heavy duck used in machine-beltting the difference in speed should be much greater. Nor do we claim as the invention of the said HAYWARD and BICKFORD the mere spreading of india-rubber upon cloth by means of heated rollers; nor the mere running of iron rollers at different velocities, as the same has been done before for the purpose of planishing a hard surface, such as that of a plate of metal, or for grinding or reducing any substances between them; but

What we do claim as the invention of the said HAYWARD and BICKFORD is—

1. The new or improved process substantially as described of applying rubber or caoutchouc not previously dissolved by a solvent or solvents to cloth, the same being accomplished by means of revolving rollers running at different velocities, and being so arranged that the rubber while the cloth is in the act of passing between two of them shall be forced and ground into the meshes or pores of the cloth by the faster or fastest roller of the set or series.

2. The new or improved fabric or article of manufacture as produced by the said new or improved process.

FRANCIS D. HAYWARD.
IRA E. SANBORN.
